Primary Examiner — T. Chase Nelson(74) *Attorney, Agent, or Firm* — Banner & Witcoff, Ltd.**CLAIM**

The ornamental design for a shoe outsole, as shown and described.

DESCRIPTION

FIG. 1 is a lateral front perspective view of a shoe outsole showing my new design;

FIG. 2 is a medial front perspective view thereof;

FIG. 3 is a bottom view thereof;

FIG. 4 is a lateral rear perspective view thereof; and,

FIG. 5 is a cross section taken through line 5-5 of FIG. 3. The two unshaded v-shaped regions between the three grooves form no part of the claimed design. The broken lines immediately adjacent to the shaded area define the bounds of the claimed design and form no part thereof. The broken lines showing the remainder of the shoe represent unclaimed subject matter and form no part of the claimed design.
